CLAIM

The ornamental design for a salt and pepper shaker, as shown and described.

DESCRIPTION

FIG. 1 is a top front perspective view thereof;
 FIG. 2 is a top rear perspective view thereof;
 FIG. 3 is a left side elevational view thereof;
 FIG. 4 is a right side elevational view thereof;
 FIG. 5 is a top plan view thereof;
 FIG. 6 is a bottom plan view thereof;
 FIG. 7 is another top front perspective view thereof; and,
 FIG. 8 is a bottom perspective view thereof.
 The broken lines in the drawings depict portions of the salt and pepper shaker that form no part of the claimed design.
